UNITED STATES PATENT OFFICE.

NATHANIEL LOMBARD, OF WORCESTER, MASSACHUSETTS.

FUEL-FEEDING DEVICE FOR INTERNAL-COMBUSTION ENGINES.

1,407,204.

Specification of Letters Patent. Patented Feb. 21, 1922.

Application filed April 21, 1918. Serial No. 291,512.

To all whom it may concern:

Be it known that I, NATHANIEL LOMBARD, a citizen of the United States, residing at Worcester, in the county of Worcester and 5 Commonwealth of Massachusetts, have invented a new and useful Improvement in a Fuel-Feeding Device for Internal-Combustion Engines, of which the following, together with the accompanying drawings, is 10 a specification.

My invention relates to fuel feeding devices for internal combustion engines by means of which fuel is delivered to the carburetor of the engine from a fuel supply 15 tank located below the level of the carburetor, the operation of the device being dependent upon the suction or vacuum created by the pistons of the engine.

The object of my invention is to provide 20 a fuel feeding device that is extremely simple in construction and reliable in operation, and by means of which a continuous supply of fuel from the supply tank to the carburetor is insured.

25 Fuel feeding devices of the suction or vacuum type, as heretofore constructed, have usually comprised a float member adapted to operate valves, for controlling the flow of fuel through the device, by means of a linkage mechanism for transmitting the motion of the float to the valves. It has been found that fuel feeding devices of this character are not always reliable in their operation, owing to the fact that the float is liable to 30 leak, or that the valve mechanism is liable to get out of order, thus causing the device to become inoperative and interrupting the supply of fuel to the carburetor.

By my invention, I provide a fuel feeding 40 device free from the above mentioned objections, in that it comprises a relatively small number of moving parts and, furthermore, is dependent upon the force of gravity for its operation rather than upon the operation of a float. In addition, my device employs sliding sleeve valves carried directly by the 45 gravity controlled member of the device, thereby eliminating any intermediate motion transmitting mechanism. The valves 50 are thus adapted to be readily removed for inspection and require practically no adjustment.

An additional advantageous feature lies 55 in the fact that the main fuel supply chamber is provided with a glass casing, so that

the operation of the device may always be observed.

In the accompanying drawings, Figure 1 is a transverse sectional view of my device, showing the parts in the positions 60 which they occupy when fuel is being drawn into the device from the supply tank.

Figure 2 is a sectional view similar to Fig. 1, showing the parts in the positions 65 which they occupy when fuel is being transferred from one container to another.

Figure 3 is a view in side elevation showing a portion of the parts shown in Fig. 1.

Like reference characters refer to like 70 parts in the different figures.

Referring to the drawings, the device comprises a cup shaped base 1 that is integral with or otherwise secured to a pipe connection 2 which is adapted to receive the end of a pipe leading from a suitable fuel supply 75 tank, not shown. The connection 2 is provided with a central opening 3 and an enlarged recess 4, within which is located a ball 5 that serves as a check valve closure for the opening 3. A casing 6, preferably 80 composed of glass or other transparent material, is carried upon a shoulder 1^a of the base 1, and a top 7 similar in form to the base 1 serves to close the upper end of the casing 6. The base 1, the casing 6, and the 85 top 7 constitute a fuel supply chamber 8 that is open to the atmosphere through a suitable aperture 9 provided in the top 7.

A vertical spindle or rod 10 is centrally located within the chamber 8 and projects 90 through suitable openings provided in the base 1 and the top 7. The lower portion of the rod 10 is provided with a central opening 11 extending from the recess 4 to a point substantially half way up the rod. The rod 95 10 is surrounded by a sleeve 12 that is slideable with respect thereto, and is provided with a plurality of radial ports 13 communicating with an annular duct 14 provided on the rod 10. The lower portion of the duct 100 14 is connected to the opening 11 by radial ports 15, so that a continuous passage from the recess 4 to the ports 13 is provided, with the parts in the position shown. A substantially spherical casing 16 is mounted on a 105 shoulder 12^a of the sleeve 12 at a point adjacent to the ports 13 and extends substantially to the top of the sleeve 12. The upper portion of the rod 10 is provided with a central opening 17 and an annular groove 18 110

which is connected to the opening 17 by a port 19. The upper end of the sleeve 12 is provided with a port 20 that registers with the groove 18 when the parts are in the position shown in Fig. 1. The rod 10 is further provided with an annular duct 21 which communicates by means of a port 22 with a tube 23 extending through the casing 16 to a point within the chamber 8, and with radial ports 24 located below correspondingly arranged ports 25 in the sleeve. The opening 17 of the rod 10 is adapted to be connected by suitable tubing, not shown, to the intake manifold of an internal combustion engine.

15 The sleeve 12 is adapted to be held in the position shown in Fig. 1 by means of arms 26 in engagement with the projection 12^a of the sleeve 12. The arms 26 are pivotally connected at their lower ends to levers 27, 20 mounted on the rod 10 by pins 28. The levers 27 are normally held toward each other by means of springs 29, thus tending to maintain the sleeve 12 in its upward position through the action of the arms 26.

25 The arms 26 and the levers 27 constitute a pair of toggle joints, the action of which will be hereinafter described.

Having thus described the parts entering into my invention, the operation thereof is 30 as follows:—Assuming that the parts occupy the position shown in Fig. 1, air within the casing 16 is drawn out through the opening 17, by means of the suction produced by the pistons of the engine. This 35 suction causes the fuel to flow from the supply pipe past the ball 5 and through the opening 11 to the ports 18 leading into the casing 16, as indicated by arrows. As soon as the weight of the fuel in the casing 16 40 overcomes the tension of the springs 29, the casing 16 together with the sleeve 12 starts to move downwardly on the rod 10. As soon as the sleeve 12 starts to move, the port 20 ceases to register with the groove 18, there- 45 by cutting off the suction from the casing 16 and allowing the ball 5 to return to its seat to prevent the back flow of fuel. The sleeve 12 continues its downward movement until the ports 24 register with the ports 25 and 50 the port 20 registers with the duct 21. At this point the casing 16 is open to atmospheric pressure through the tube 23, and the ports 22 and 20 whereupon the fuel within the casing passes through the ports 13 directly to the ports 24 and 25 and thence into the chamber 8, as indicated by arrows in 55 Fig. 2. From the chamber 8 the fuel flows to the carbureter through a suitable supply pipe 30 located at the bottom of the chamber 8. The action of the toggle joints formed 60 by the arms 26 and the levers 27 causes the device to positively operate as soon as a predetermined amount of fuel has accumulated in the casing 16. It is obvious from an inspection of the drawing that as soon as the casing 16 starts to move downwardly the levers 27 move outwardly, thereby increasing the lever arms through which the combined weights of the casing and the fuel therein act against the springs 29. Consequently when the casing 16 once starts to move downwardly it passes from the position shown in Fig. 1 to the position shown in Fig. 2 with one continuous movement, for the combined weights of the casing and fuel 70 are always sufficient to overcome the resistance of the springs 29 owing to the increased leverage. The casing 16 returns to its original position after discharging the fuel 75 therein with a continuous upward movement owing to the constantly decreasing force exerted by the weight of the casing in its upward movement. As a result of the above 80 described action the valve ports are always either entirely closed or entirely open. 85

From the foregoing, it is apparent that the chamber 8 will be continuously supplied with fuel by the successive filling and emptying of the casing 16. In case the fuel is supplied to the chamber 8 faster than it is 90 consumed by the carbureter, the spherical casing 16 will tend to balance upon the fuel in the chamber and prevent the ports 24 and 25 from registering and permitting any additional fuel to flow into the chamber 8. It 95 is also apparent that my device comprises no complicated valve mechanism that is liable to get out of order and that the spherical form of the casing 16 practically eliminates any possibility of it becoming jammed 100 within the casing 6. The operation of the device as a whole is also open to inspection at all times through the transparent casing 6 and the sliding valve members can be readily removed for inspection by merely 105 removing the top 7 and pulling out the valve rod 10 and its sleeve 12.

I claim,

1. In a fuel feeding device, a fuel container mounted on a vertical spindle, and a second fuel container located within the first named container and carried on a sleeve in sliding engagement with said spindle, the said spindle and the said sleeve being provided with valve passages for controlling 110 the flow of fuel between said containers.
2. In a fuel feeding device, a vertical spindle surrounded by a fuel chamber, and a sleeve slidably mounted on said spindle and carrying a fuel container, the said spindle and the said sleeve being provided 115 with valve passages for controlling the flow of fuel between said container and said chamber, as said container moves under the force of gravity.
3. In a fuel feeding device, the combination with a vertical spindle surrounded by a fuel chamber and a sleeve slidably mounted on said spindle and carrying a fuel container, of means for exhausting air from 120

said container at the top of said spindle and check-valve controlled means for admitting fuel to said container at the bottom of said spindle.

5 4. In a fuel feeding device, the combination with a vertical spindle surrounded by a fuel chamber and a sleeve slidably mounted on said spindle and carrying a fuel container, of means for admitting air under 10 atmospheric pressure to said container at the top of said spindle, and for connecting said container to said chamber at a point intermediate the ends of said spindle.

5. In a fuel feeding device, the combination with a vertical spindle surrounded by a fuel chamber and a sleeve slidably mounted on said spindle and carrying a fuel container, of valve passages provided in said spindle and in said sleeve respectively for 15 exhausting air from said container and for admitting fuel thereto in one position of said sleeve relative to said spindle, and for admitting air under atmospheric pressure to said container and for connecting said container to said chamber in another position 20 of said sleeve relative to said spindle.

6. In a fuel feeding device, a movable fuel container provided with means for exhausting air at the top thereof, and for admitting 25 fuel at the bottom thereof.

7. In a fuel feeding device, the combination with a fuel chamber and a relatively movable fuel container located therein, of means for exhausting said container and admitting fuel thereto in one position of said container, and separate means for admitting air under atmospheric pressure to said container, and for connecting said container to said chamber in another position of said 30 container.

8. In a fuel feeding device, the combination with a fuel chamber and a relatively movable fuel container located therein, of suction-operated means for accumulating fuel in said container in one position thereof,

whereby a predetermined accumulation of fuel will cause said container to move within said chamber to cut off said suction-operated means, and to connect the interior of said container to the atmosphere and the outlet 50 of said container to the said chamber.

9. In a fuel feeding device, the combination with a fuel chamber and a relatively movable fuel container located therein, of suction-operated means for accumulating 55 fuel in said container in one position thereof, whereby a predetermined accumulation of fuel will cause said container to move within said chamber to cut off said suction-operated means, and to discharge the fuel into said 60 chamber at atmospheric pressure.

10. In a fuel feeding device, the combination with a fuel chamber and a vertically movable fuel container located therein, of means for opposing downward movement of 65 said container upon the accumulation of fuel therein, the weight of said container and fuel acting through an increasing lever arm against the opposing means as said container moves downwardly. 70

11. In a fuel feeding device, the combination with a fuel chamber and a vertically movable fuel container located therein, of a spring actuated device for opposing downward movement of said container upon the 75 accumulation of fuel therein, the weight of said container and fuel acting through an increasing lever arm upon said device as said container moves downwardly.

12. In a fuel feeding device, the combination with a fuel chamber and a vertically movable fuel container located therein, the movement of which controls the flow of fuel from said container to said chamber, of a spring-actuated toggle device for maintaining 80 said container in its upper position. 85
